Application August 17, 1945, Serial No. 611,182

17 Claims. (Cl. 179—171)

1

This invention relates to equalizing repeating systems and, while it is of general application, it is particularly suitable for use in universal equalizing amplifiers for wave-signal translating systems and apparatus, including sound responding, recording and reproducing circuits and apparatus, telephone lines and the like.

In audio-frequency signal responding, recording and reproducing systems, it often occurs that certain apparatus incorporated in the system or certain portions of the circuit itself have substantially non-linear frequency-response characteristics which, if uncompensated, introduce distortion into the output of the system. Furthermore, it frequently occurs that such audio-frequency systems must be used in conjunction with different signal-translating apparatus, for example different microphones, or different sound-reproducers, so that it is not possible to design the several components of the system to work permanently with each other. It is an object of the invention, therefore, to provide a new and improved equalizing repeating system which is particularly useful as a universal component of audio-frequency systems of the type described, for compensating for, or matching, the non-linear frequency-response characteristic of one or more of the other components of the system.

It is another object of the invention to provide a new and improved equalizing repeating system by means of which the response at any particular frequency or any portion of the frequency range over which the system is to operate may be adjustably and selectively attenuated or amplified to a high degree with respect to that over the remainder of the frequency range.

In accordance with the invention, an equalizing repeating system for translating wave signals within a given frequency range with an adjustable repeating ratio over a predetermined portion of the frequency range comprises a signal input circuit, a signal output circuit, a first signal-translating channel coupled between the input and output circuits and having a substantially constant repeating ratio over such frequency range, and a second signal-translating channel coupled between the input and output circuits and having a repeating ratio over such predetermined portion of the range substantially different from that over the remainder of the range. The system also includes means for adjusting the relative amplitudes of the signal outputs of the channels, as by adjusting the relative amplitudes of the signal inputs thereto, to maintain the sum of the signal outputs of the two channels approxi-

2

mately constant at frequencies over the remainder of the frequency range.

For a better understanding of the invention, together with other and further objects thereof, reference is had to the following description taken in connection with the accompanying drawings while its scope will be pointed out in the appended claims.

Referring now to the drawings, Fig. 1 is a circuit diagram of an equalizing repeating system embodying the invention; Fig. 2 is a graph illustrating certain operating characteristics of the system of Fig. 1 to aid in the understanding of the invention; while Fig. 3 is a circuit diagram of a modified system having operating characteristics similar to those of Fig. 1.

Referring now to Fig. 1 of the drawings, there is represented an equalizing repeating or amplifying system for translating wave signals within a given frequency range with an adjustable repeating ratio or gain over a predetermined portion of the frequency range, for example with an adjustable peaked response, either positive or negative, at a predetermined frequency of the range. This system comprises a signal-input circuit having terminals 10, 10 and a signal-output circuit having terminals 11, 11. A first signal-translating channel is coupled between the input circuit 10 and the output-circuit 11 including a vacuum tube 12 of any suitable type and the channel including the tube 12 is designed to have a substantially constant repeating ratio or gain over the entire frequency range. The signal-input electrode or grid of the tube 12 is connected to the input circuit 10 through a voltage-divider network to be described hereinafter and an isolating resistor 13. The tube 12 is also provided with a suitable grid-return resistor 14 and a cathode-bias resistor 15. Space current is supplied to the anode of the tube 12 through a load resistor 16 from a suitable source +B, as indicated. The anode of the tube 12 is coupled to the output circuit 11 through a blocking condenser 17.

The equalizing system of Fig. 1 also includes a second signal-translating channel coupled between the input circuit 10 and the output circuit 11 and including a plurality of vacuum tubes, for example three tubes 18, 19 and 20 coupled in cascade and designed to have a repeating ratio or gain over such predetermined portion of the frequency range substantially different from that over the remainder of the range. For example, the second channel may be designed to have a peaked response at said predetermined frequency

and to have a repeating ratio or gain over the remainder of the frequency range substantially equal to that of the first channel including the vacuum tube 12. The signal-input electrode or grid of the first tube 18 of the second channel is coupled to the input circuit 10 through a voltage-divider network to be described hereinafter and an isolating resistor 21. The control electrode of the tube 18 is also provided with a pair of grid return resistors 22 and 23 in series and a cathode-bias resistor 24. Space current is supplied to the tube 18 through a load resistor 25 from a suitable source +B, as indicated. The anode of the tube 18 is coupled to the signal-input electrode to the second tube 19 through a coupling condenser 27 and a grid resistor 28, the tube 19 being provided with a cathode-bias resistor 29 and being supplied with space current through a load resistor 30 from a suitable source +B, as indicated. Similarly, the anode of the tube 19 is coupled to the signal-input electrode of the third tube 20 through a coupling condenser 31 and a grid resistor 32, the cathode of the tube 20 being provided with a bias resistor 33 and the anode of the tube 20 being provided with space current through a resistor 34 in parallel with a load circuit comprising a blocking condenser 35 and resistors 36 and 37 in series.

If desired, the anode of the tube 20 may be connected in parallel with the anode of the tube 12 in the first channel to translate the signal to the output circuit 11. However, it is preferable, as shown, to utilize an auxiliary isolating tube 38 having its control electrode connected in parallel with the control electrode of the tube 20 and having its anode connected in parallel with the anode of the tube 12, so that it is supplied with space current from the source +B through the common load resistor 16. The tube 38 may be provided with a suitable cathode bias resistor 39. The tubes 12 and 38 should have identical electrical characteristics.

The described characteristics may be imparted to the second channel including the tubes 18, 19, 20 and 38 by designing it to have a normal gain substantially greater than that of the first channel, which it normally does have by virtue of its cascade-coupled vacuum-tube amplifiers, but including means for reducing the gain thereof over the remainder of the frequency range. This means may take the form of a degenerative feedback circuit 40 coupled between the load resistor 37, and thus to the output electrode of the third vacuum tube 20, and the grid resistor 23, and thus to the input electrode of the first vacuum tube 18. The feedback circuit 40 is designed to be unresponsive at the predetermined portion of the frequency range over which an adjustable repeating ratio is desired. The feedback circuit 40 may be of any conventional type having the desired frequency-response characteristic but there is illustrated by way of example a feedback network comprising a double-T resistance-capacitance bridge designed to resonate at the predetermined frequency at which the peaked response is desired. Specifically, the network 40 comprises a first T including series-capacitance arms 41 and 42 and a shunt resistance arm comprising a fixed resistor 43 in series with an adjustable resistor 44. The second T of the network includes series-resistance arms comprising respectively, an adjustable resistor 45 in series with the fixed resistor 46 and an adjustable resistor 47 in series with the fixed resistor 48, and a shunt-capacitance arm 49.

The equalizing repeating system of the invention also includes means for adjusting the relative amplitudes and polarities of the signal outputs of the two channels to maintain the sum thereof approximately constant at the frequencies over such remainder of the frequency range. This means is preferably in the form of means interposed between the input circuit 10 and the two channels for adjusting the relative amplitudes and polarities of the signal inputs to the channels to maintain the sum of the signal outputs over the remainder of the frequency range constant. For example, the signal-input circuit 10 may be connected to a primary winding 50a of a transformer 50 having a secondary winding 50b, the midpoint of which is grounded to provide the signal-input circuit with an intermediate point of reference potential. Voltage divider means are connected across the input circuit, specifically a pair of voltage dividers effectively in parallel across the secondary winding 50b. One of the voltage dividers 51 is connected between the upper terminal of the winding 50b and ground, while the second voltage divider 52 is connected across the secondary winding 50b through fixed resistors 53 and 54. The voltage dividers 51 and 52 are provided with adjustable contacts 51a and 52a, respectively, which are individually connected to the signal input electrodes of the tubes 12 and 18 in the two signal-translating channels. The adjustable contacts 51a and 52a are connected by a unicontrol mechanism indicated schematically by the dot-dash-line 55 for simultaneously adjusting the contacts in opposite potential senses and, as explained hereinafter, for adjusting only one of the contacts, namely the contact 52a, through the point of reference potential during the adjustment of the contact 51a over its respective range. As indicated schematically, the voltage dividers 51 and 52 are preferably logarithmically tapered or shaped so that the contacts 51a and 52a have a linear gain-adjustment characteristic on a decibel scale.

In explaining the operation of the system of Fig. 1, described above, it will be assumed that the adjustable contacts 51a and 52a are adjustable between their limiting dotted-line and dot-dash-line positions as represented. It is also assumed that the constants of the voltage divider resistors 51 and 52 and the fixed resistors 53 and 54 are so proportioned that the signal potentials appearing at the limiting and mid positions of the adjustable contacts 51a and 52a have the relative values indicated on the voltage dividers at the several points, it being understood that these figures are given to designate relative values only, for the purpose of illustration, and that the absolute values may vary within wide limits in accordance with the nature of each particular installation. It is also assumed that the gain μ_1 of the first channel is 10 at all frequencies within the range to be translated and that the normal gain μ_2 of the second signal-translating channel is 100. It is also assumed that the circuit constants of the feedback circuit including resistors 37 and 23 and the degenerative network 40 are so proportioned as to reduce the gain μ_2 of the second channel over the remainder of the frequency range to a value of 10, that is, to a value equal to that of the first channel. At the resonant frequency of the network 40, it presents a substantially infinite impedance so that the second channel is not degenerative at this frequency but has its normal gain μ_2 of 100.

With the foregoing assumptions and with the

adjustable contacts 51a and 52a in their dotted-line positions, it is seen that no signal is applied to the first signal channel so that its output will be zero. At the same time, one unit of the signal is applied to the second channel which, with a gain μ_3 of 100, would result in an output signal of 100 units at the predetermined frequency at which the degenerative network 40 is resonant. However, due to the loading of the inactive vacuum tube 12, this signal output as impressed upon the output circuit 11 is reduced to 50 units. Over the remainder of the frequency range the degenerative network 40 reduces the gain of the second channel to 10 so that its signal output is 10 units, which is reduced by the loading of the tube 12 to 5 units. The resulting characteristic of the system with the contacts 51a and 52a in this position is represented by Curve A of Fig. 2 in which the ordinates represent signal output on a logarithmic scale and the abscissae represent frequency on a linear scale. It will be understood that the sharpness of the response at the frequency f_0 may be adjusted within wide limits by the proper design of the degenerative network 40.

Assume now that the adjustable contacts 51a and 52a occupy their intermediate solid-line positions. Under these conditions, one unit of signal input is applied to the first channel which, increased by the gain of 10 of this channel and reduced by the loading of the parallel tube 38, results in a signal output of 5 units over the entire frequency range. At the same time, the signal input to the second channel is zero so that it produces no signal output and the total output of the system is that of the first channel and is represented by Curve B of Fig. 2. Obviously for positions of the adjustable contacts 51a and 52a intermediate the two positions just described, a series of curves intermediate Curves A and B will represent the overall response characteristics of the system.

If now the adjustable contacts 51a and 52a are moved to their lower dot-dash-line positions, it is seen that a signal of 1.10 units is applied to the first channel including the tube 12 and that a negative signal input of 0.10 unit is applied to the second channel. Considering the first action at the frequency f_0 , the signal output of the first channel is 11 units which is reduced by the loading of the tube 38 to 5.5 units. At the same time, the signal output of the second channel is -10 units which is reduced by the loading of the tube 12 to a -5.0 units so that the resultant signal output at the frequency f_0 is 0.5 signal units. Over the remainder of the frequency range, the signal output of the first channel is likewise 5.5 units, while the signal output of the second channel is -1 unit which is decreased by the loading of the tube 12 to -0.5 unit so that the resultant signal output of the system is 5.0 units. This is represented by Curve C of Fig. 2. Obviously, for positions of adjustable contacts 51a and 52a intermediate the last two positions described, there results a series of curves intermediate Curves B and C.

Thus it is seen that, by the use of the equalizing system of the invention, there is procured a resultant repeating ratio or gain which has a peaked response at a predetermined frequency f_0 within the range which is adjustable between maximum and minimum values, while the repeating ratio or gain over the remainder of the fre-

quency range is maintained substantially constant. It will be apparent that, by simultaneously and appropriately adjusting certain elements of the degenerative feedback network 40, for example resistors 44, 45 and 47, the frequency of resonance f_0 of the network 40 may be shifted over a wide range within the operating frequency range of the system. By a combination of the adjustment of the resonant frequency of the network 40 and of the adjustable contacts 51a and 52a, a wide variety of overall-response characteristics may be obtained which are capable of compensating for, or matching, the non-linear-response characteristics of a wide variety of sound-translating apparatus.

By the use of the logarithmically tapered voltage dividers 51 and 52, the adjustable contacts 51a and 52a produce a linear variation in the peaked response of the system on a decibel scale. This is represented in Fig. 2 in which the maximum emphasis at the frequency f_0 is +20 decibels, while the maximum attenuation is -20 decibels. In general, if the adjustable contact 51a is adjustable over the range $0-p_1-p_2$ while the contact 52a is simultaneously adjustable over the signal potential range $p_3-0-(-p_4)$, representing the three positions of these contacts illustrated in the drawing, and the circuit constants of the system are proportioned to satisfy the relations:

$$p_1\mu_1 = p_3\mu_2$$

$$(p_2-p_1)\mu_1 = p_4\mu_2$$

$$\frac{p_3\mu_3}{p_1\mu_1} = \frac{p_1\mu_1}{p_2\mu_1 - p_4\mu_3}$$

the repeating ratio is maintained constant over the remainder of the frequency range while it is adjustable over the predetermined portion of the frequency range by equal amounts, in decibels, above and below that of the remainder of the range.

Referring now to Fig. 3, there is represented a modified equalizing repeating system in which several of the component elements are the same in construction and operation as those of Fig. 1 and are identified by the same reference numerals. In the system of Fig. 3, the adjustable voltage divider 52 is replaced by a fixed voltage divider 60 having terminals 60a and 60b at the points of signal potential corresponding to the limiting positions of the adjustable contact 52a of Fig. 1. The potentials of these two points are selectively applied to the second channel by means of a switch 61 having contacts 61a and 61b connected to the points 60a and 60b, respectively, and extending over a range equal to the range of adjustment of the adjustable contact 51a. In this modification, the second tube 19 of Fig. 1 is replaced by a cathode-follower tube 62 having a cathode-biasing circuit 63 and a cathode-load resistor 64 which is coupled through a condenser 65 and the selective degenerative feedback network 40 to the grid resistor 23 in the input circuit of the tube 18. With this arrangement, as is well known, the signal is not reversed in polarity at the output circuit of the tube 62 so that, if the system is designed with adequate gain, only two rather than three tubes need be provided in the second channel.

In the arrangement of Fig. 3, the adjustment of the signal output potential of the second channel is effected by a pair of voltage dividers 66 and 67 interposed in parallel in the second channel, as

by connecting them across the signal channel at the output circuit of tube 18 through a coupling condenser 67. The voltage dividers have a common adjustable contact 68 disposed selectively to engage the dividers 65 and 66 and connected to the signal-input electrode of the isolating tube 38. There is provided a unicontrol mechanism, represented schematically by the dot-dash-line 69, for simultaneously actuating the adjustable contacts 51a and 68 and the switch 61. The switch 61 derives from the input circuit and applies to the second channel signals of predetermined different values and opposite polarities for different portions of the range of adjustment of the contact 51a, while the adjustable contact 68 selectively engages the voltage dividers 65 and 66 in accordance with the polarity of the signal applied to the second channel.

The principles of operation of the system of Fig. 3 are entirely similar to those of the system of Fig. 1, the adjustment of the signal output of the second channel being effected by means of the voltage dividers 65 and 66 at an intermediate point in the channel, rather than by the voltage divider 52 of Fig. 1 at the input of the channel. The contacts 61a and 61b are effectively cross-connected to the contacts 60a and 60b, respectively, to take into consideration the reversal of the polarity of the signal output of the tube 18 with respect to the signal input to the second channel.

While there have been described what are at present considered to be the preferred embodiments of the invention, it will be apparent to those skilled in the art that various changes and modifications may be made therein without departing from the spirit or scope of the invention.

What is claimed as new is:

1. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, and means for adjusting the relative amplitudes of the signal outputs of said channels in opposite senses to maintain the sum thereof approximately constant at frequencies over said remainder of said frequency range.

2. An equalizing amplifying system for translating wave signals within a given frequency range with an adjustable gain over a predetermined portion of said frequency range comprising, a signal input circuit, a signal output circuit, a first signal-translating channel coupled between said input and output circuits and having a substantially constant gain over said frequency range, a second signal-translating channel coupled between said input and output circuits in aiding phase with respect to said first channel and having a gain over said predetermined portion of said range substantially different from that over the remainder of said range, and means for adjusting the relative amplitudes of the signal outputs of said channels in opposite senses to maintain the sum thereof approxi-

mately constant at frequencies over said remainder of said frequency range.

3. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range and having a repeating ratio over said remainder of said range substantially equal to that of said first channel, and means for adjusting the relative amplitudes of the signal outputs of said channels in opposite senses to maintain the sum thereof approximately constant at frequencies over said remainder of said frequency range.

4. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, and means for adjusting the relative amplitudes and polarities of the signal outputs of said channels in opposite senses to maintain the sum thereof approximately constant at frequencies over said remainder of said frequency range.

5. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, and means for adjusting the relative amplitudes of the signal inputs of said channels in opposite senses to maintain the sum of the signal outputs thereof approximately constant at frequencies over said remainder of said frequency range.

6. An equalizing repeating system for translating wave signals within a given frequency range with an adjustable peaked response at a predetermined frequency of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a peaked response at said

predetermined frequency, and means for adjusting the relative amplitudes of the signal outputs of said channels in opposite senses to maintain the sum thereof approximately constant at frequencies over said remainder of said frequency range.

7. An equalizing amplifying system for translating wave signals within a given frequency range with an adjustable gain over a predetermined portion of said frequency range comprising, a signal input circuit, a signal output circuit, a first signal-translating channel coupled between said input and output circuits including a vacuum tube and having a substantially constant gain over said frequency range, a second signal-translating channel coupled between said input and output circuits in aiding phase with respect to said first channel and including a plurality of vacuum tubes in cascade and having a normal gain substantially greater than that of said first channel but including means for reducing the gain thereof over the remainder of said frequency range, and means for adjusting the relative amplitudes of the signal outputs of said channels in opposite senses to maintain the sum thereof approximately constant at frequencies over said remainder of said frequency range.

8. An equalizing amplifying system for translating wave signals within a given frequency range with an adjustable gain over a predetermined portion of said frequency range comprising, a signal input circuit, a signal output circuit, a first signal-translating channel coupled between said input and output circuits including a vacuum tube and having a substantially constant gain over said frequency range, a second signal-translating channel coupled between said input and output circuits in aiding phase with respect to said first channel and including a plurality of vacuum tubes in cascade and having a normal gain substantially greater than that of said first channel but including degenerative feedback means unresponsive at said predetermined portion of said frequency range, and means for adjusting the relative amplitudes of the signal outputs of said channels in opposite senses to maintain the sum thereof approximately constant at frequencies over said remainder of said frequency range.

9. An equalizing amplifying system for translating wave signals within a given frequency range with an adjustable gain over a predetermined portion of said frequency range comprising, a signal input circuit, a signal output circuit, a first signal-translating channel coupled between said input and output circuits including a vacuum tube and having a substantially constant gain over said frequency range, a second signal-translating channel coupled between said input and output circuits in aiding phase with respect to said first channel and including three vacuum tubes in cascade and having a normal gain substantially greater than that of said first channel but including degenerative feedback means coupled from the output electrode of the third of said tubes to the input electrode of the first thereof, said feedback means being unresponsive at said predetermined portion of said frequency range, and means for adjusting the relative amplitudes of the signal outputs of said channels in opposite senses to maintain the sum thereof approximately constant at frequencies over said remainder of said frequency range.

10. An equalizing amplifying system for translating wave signals within a given frequency

range with an adjustable gain over a predetermined portion of said frequency range comprising, a signal input circuit, a signal output circuit, a first signal-translating channel coupled between said input and output circuits including a vacuum tube and having a substantially constant gain over said frequency range, a second signal-translating channel coupled between said input and output circuits in aiding phase with respect to said first channel and including a plurality of vacuum tubes in cascade and having a normal gain substantially greater than that of said first channel but including degenerative feedback circuit including a double-T resistance-capacitance bridge resonant at a frequency in said predetermined portion of said frequency range, and means for adjusting the relative amplitudes of the signal outputs of said channels in opposite senses to maintain the sum thereof approximately constant at frequencies over said remainder of said frequency range.

11. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, and means interposed between said input circuit and said channels for adjusting the relative amplitudes of the signal inputs to said channels in opposite senses to maintain the sum of the signal outputs thereof approximately constant at frequencies over said remainder of said frequency range.

12. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, and voltage-divider means connected across said input circuit and including a pair of adjustable contacts individually connected to said channels for adjusting the relative amplitudes of the signal inputs to said channels in opposite senses to maintain the sum of the signal outputs thereof approximately constant at frequencies over said remainder of said frequency range.

13. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first

11

channel and having a repeating ratio over said predetermined portion of said range substantially different from that over the remainder of said range, a pair of voltage dividers connected in parallel across said input circuit, each having an adjustable contact, said contacts being individually connected to said two channels, and means for adjusting said contacts in opposite potential senses for adjusting the relative amplitudes of the signal inputs to said channels to maintain the sum of the signal outputs thereof approximately constant at frequencies over said remainder of said frequency range.

14. An equalizing repeating system for translating wave signals within a given frequency range with an adjustable repeating ratio over a predetermined portion of said frequency range comprising, a signal input circuit having an intermediate point of reference potential, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, a pair of voltage dividers connected in parallel across said input circuit, each having an adjustable contact, said contacts being individually connected to said two channels, and means for adjusting said contacts in opposite potential senses and for adjusting only one of said contacts through said point of reference potential for adjusting the relative amplitudes and polarities of the signal inputs to said channels to maintain the sum of the signal outputs thereof approximately constant at frequencies over said remainder of said frequency range.

15. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio μ_1 over said frequency range, a second signal-translating channel coupled between said input and output circuits in aiding phase with respect to said first channel and having a repeating ratio μ_3 over said predetermined portion of said range substantially different from that over the remainder of said range and having a repeating ratio μ_2 over said remainder of said range, a pair of voltage dividers connected in parallel across said input circuit, each having an adjustable contact, a first of said contacts being connected to said first channel and being adjustable over a signal potential range $0-p_1-p_2$ and the other of said contacts being connected to said second channel and simultaneously adjustable over a signal potential range $p_3-0-(-p_4)$, the constants of the circuit being proportioned to satisfy the relations:

$$p_1\mu_1 = p_3\mu_2$$

$$(p_2-p_1)\mu_1 = p_4\mu_2$$

$$\frac{p_3\mu_3}{p_1\mu_1} = \frac{p_1\mu_1}{p_2\mu_1 - p_4\mu_2}$$

whereby the repeating ratio of the system is maintained constant over said remainder of said

12

range and the repeating ratio over said predetermined portion of said range is adjustable by equal amounts, in decibels, above and below that over said remainder of said range.

16. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits and having a substantially constant repeating ratio over said frequency range, a second signal-translating channel coupled between said input and output circuits in aiding phase with respect to said first channel and having a repeating ratio over said predetermined portion of said range substantially different from that over the remainder of said range, and means for adjusting the relative amplitudes of the signal outputs of said channels to maintain the sum thereof approximately constant at frequencies over said remainder of said frequency range comprising a voltage divider connected across said input circuit having an adjustable contact connected to said first channel, switch means for deriving from said input circuit and applying to said second channel signals of predetermined different values and opposite polarities for different portions of the range of adjustment of said contact, a pair of voltage dividers interposed in parallel in said second channel and having a common adjustable contact disposed selectively to engage said pair of dividers in accordance with the polarity of the signal applied to said second channel, and unicontrol means for actuating said adjustable contacts and said switch means in unison.

17. An equalizing repeating system for translating wave signals within a given frequency range with an adjustable repeating ratio over a predetermined portion of said frequency range comprising, a signal input circuit, a signal output circuit, a first signal-translating channel coupled between said input and output circuits including a single vacuum tube and having a substantially constant repeating ratio over said frequency range, a second signal-translating channel coupled between said input and output circuits in aiding phase with respect to said first channel and including two vacuum tubes the second of which has a cathode load circuit, said second channel having a normal gain substantially greater than that of said first channel but including degenerative feedback means coupled from said cathode load circuit to the input electrode of the first tube thereof, said feedback means being unresponsive at said predetermined portion of said frequency range.
